UNITED STATES PATENT OFFICE

2,052,482

SPINNER MACHINE IRON HEAD CLEANER

Frank Mont, Nanticoke, Pa.

Application May 7, 1935, Serial No. 20,244

1 Claim. (Cl. 15—21)

The invention relates to a cleaning machine and more especially to a machine for cleaning the flange of an iron head employed in a spinner or twister machine used in throwing silk yarns. 5 The primary object of the invention is the provision of a machine of this character, wherein the iron heads can be handled automatically and are conveyed to a brush working in a cleaning fluid that will remove dirt or other foreign 10 matter from the flanges of the said iron heads during the travel of these through the machine.

Another object of the invention is the provision of a machine of this character, wherein the construction thereof is novel in form and will 15 enable the automatic feeding of the iron head and the delivery of the same to and from the machine, the iron heads when within the machine will be readily and satisfactorily cleaned without manual handling thereof.

20 A further object of the invention is the provision of a machine of this character, which is comparatively simple in its construction, automatic in operation, thoroughly reliable and efficient in the functioning thereof, strong, durable, 25 and inexpensive to manufacture and install.

With these and other objects in view, the invention consists in the features of construction, combination and arrangement of parts as will be hereinafter more fully described, illustrated in 30 the accompanying drawings, which disclose the preferred embodiment of the invention and pointed out in the claim hereunto appended.

In the accompanying drawings:

Figure 1 is a top plan view of the machine constructed in accordance with the invention.

Figure 2 is a side elevation thereof.

Figure 3 is a fragmentary side elevation partly in section.

Figure 4 is a sectional view on the line 4—4 of Figure 2 looking in the direction of the arrows.

Figure 5 is a fragmentary perspective view showing in detail the cleaner brushes as used in the machine.

Similar reference characters indicate corresponding parts throughout the several views in the drawings.

Referring to the drawings in detail, the machine comprises a frame A substantially skeleton in form and including the outer and intermediate uprights 10 and 11, these being spaced the required distance apart with respect to each other. Arranged intermediate of the frame A and suitably journaled in the uprights 11 is an axle or shaft 12 on which are fitted carrier wheels 13, these being arranged next to iron head clean-

ing brushes 14 upon a shaft 15 journaled in bearings 16. The brushes 14 operate in pockets 17, these being formed in a cleaning fluid tank or trough 18 built within the frame A of the machine. The tank or trough is fitted with a drain cock 19 so that the contents may be drawn off at will, the cock being manually controlled.

Supported within the frame A by selected uprights 10 and 11 is a feed conveyor or chute 20 having the inclined spout portion 21 which directs iron heads 22 on to the carrier wheels 13 so that the flanges of these iron heads will be acted upon by the brushes 14 when operating for the thorough cleaning thereof.

Directly over the wheels 13 are presser rollers 15 23, these being journaled in forks 24, their stems 25 being extended vertically through guides 26. Surrounding the stems 25 are tensioning springs 27. The springs 27 urge the rollers 23 into contact with the iron heads to hold the same in position upon the wheels 13 and for action thereon by the brushes 14 for cleaning purposes.

Located within the frame A at the delivery or discharge end is a delivery or discharge chute 28 for accommodating the cleaned iron heads 22 25 and delivering the same from the machine. Between the conveyor 20 and the chute 28 is a transfer device including a pair of spaced disks 29 fixed to an axle 30 suitably journaled in the frame A and at diametrically opposite points of 30 these disks 29 are grab claws 31 which travel in the path of an iron head when in position for cleaning by the brushes 14 so as to pick up singly the cleaned iron head and dispense it into the delivery or discharge chute 28 for final delivery 35 from the machine.

On the axle 15 for the brushes 14 is a belt pulley 32 while on the shaft 30 for the disk 29 is a belt wheel 33, these having trained thereover the belt 34. The belt wheel 33 is formed with an additional belt wheel 35 over which is trained a driven belt 36 the same being also trained over a pulley 37 operated by a train of gearing 38 driven from a motor 39 of the electric type. Thus this motor will drive the brushes 14 and also 45 the pick-up disk 29 for the successful working of the machine.

Arranged within the feed conveyor 20 at the upper end of the spout 21 is a gate 40, it being swingingly supported about a pivot 41 for supports 41 for said gate. Connected with the supports 41 for the gate is a crank arm 42 having pivoted at 43 thereto a shift rod 44 operating through guides 45 and this rod is operated upon by a tripper 46 upon the shaft 30. The tripper 55

intermediately actuates the rod 44 so as to periodically open the gate 39 for allowing an iron head to pass to the brush in the spout 21 for cleaning purposes. The iron heads as contained 5 within the conveyer 20 are finally delivered to cleaning position or for action thereon by the brushes 14.

Connected with the crank 42 is a coiled tensioning spring 47 which normally holds the gate 10 39 in closing position in the conveyer 20 to exclude iron heads from the spout 21 until the said gate is automatically opened.

The stems 25 for the presser rollers 23 are extended upwardly above the frame A and terminate 15 in hand grips 48 so that these rollers 23 can be manually raised against the resistance of the spring 27, the latter normally holding the same in working relation to an iron head.

The motor 39 is suitably supported within the 20 frame and is operated from an electric power line (not shown).

A cleaning solution is placed within the tank or trough 18 whence it will be delivered to the brushes 14 and these when engaging an iron head 25 will thoroughly clean the flanges thereof, the iron heads being conveyed to the brushes 14 by the conveyer 20 and the delivery or feed is had in single order and intermittently. When the iron heads have been cleaned each is transferred to 30 the delivery chute 28 whence the same is dispensed from the machine. The machine in the working thereof is automatic thus avoiding the necessity of the hand cleaning of the iron heads when fed thereto.

35 The conveyer 20 and the chute 28 each have side guards 49 to prevent the iron heads from lateral displacement during the travel thereof through the machine.

The tank or trough 18 is readily accessible for the filling thereof with a cleaning fluid, the latter being preferably gasoline although any other liquid or fluid may be employed.

When the iron head is subjected to cleaning 5 action by the brushes 14 the same will be rotated and a thorough cleaning of such head is assured. The iron head 22 is a take-up bobbin as employed in a spinner or twister for throwing silk yarns.

What is claimed is:

10 A machine of the kind described comprising a skeleton frame having intermediate and outer uprights, a shaft journaled transversely of the frame in intermediate uprights thereof, carrier wheels fixed to said shaft, a second shaft journaled close to the first-named shaft and having iron head cleaning brushes, a cleaning fluid tank disposed in said frame and having pockets accommodating the cleaning brushes, a feed chute above the tank and having an inclined spout for 20 directing iron heads onto the carrier wheels so that flanges of said iron heads will be acted upon by the brushes, presser rolls acting above the wheels for contact with the iron heads to hold the same in position upon the wheels, a 25 delivery chute in said frame and elevated relative to said wheels, a transfer device including a pair of spaced disks rotatably supported in the frame and having diametrically opposed grab claws for travel in the path of the iron heads 30 when in position for cleaning by the brushes to automatically pick up singly the cleaned iron heads and place the same in the delivery chute, and means controlled by the rotation of said spaced disks for feeding of the iron heads from 35 the feed chute into the spout.

FRANK MONT.
